UNITED STATES PATENT OFFICE.

MARIE E. SHAY, OF FORDHAM, ASSIGNOR TO MARY A. SEITZ, OF NEW YORK, N. Y.

MACHINE FOR ROLLING AXLES, SPINDLES, AND OTHER METAL ARTICLES.

SPECIFICATION forming part of Letters Patent No. 311,924, dated February 10, 1885.

Application filed January 29, 1884. (No model.)

To all whom it may concern:

Be it known that I, MARIE E. SHAY, of Fordham, in the county of New York and State of New York, have invented certain new and useful Improvements in Machines for Forging Cylindrical, Tapering, and other Shaped Articles, of which the following is a full, clear, and exact description.

This invention is more especially designed for forging axles, spindles, and other metal articles of cylindrical or tapering shape, either solid or hollow, and will here be described more particularly with reference to such use. It may also be used, however, for flat or square work.

The main object of the invention is to forge articles as above named without that waste of metal which naturally attaches to drop-forging, and to provide for the work being done expeditiously and generally at a single heat, as well as to insure a superior quality of work by giving twist to the fiber of the metal under the process of being drawn out or forged.

The invention consists in a novel method of and means for forging metal blanks by subjecting them to the action of a rotating die and a stationary or flat die, the one of said dies being adjustable toward the other to give the necessary pressure, and the rotating die preferably having oblique corrugations or grooves on its acting surface, substantially as hereinafter described.

Reference is to be had to the accompanying drawings, forming part of this specification, in which similar letters of reference indicate corresponding parts in all the figures.

Figure 1 represents a partly-broken plan view of a machine embodying my invention, with its parts constructed and arranged for making axles. Fig. 2 is a vertical longitudinal section of the same on the line $x-x$ in Fig. 1, and showing an axle-blank in the course of being shaped or forged by the machine. Fig. 3 is a front end view of the machine. Fig. 4 is a vertical transverse section of the stationary die and a spring-follower used in connection therewith. Fig. 5 is a transverse vertical section of the machine on the line $y-y$ in Fig. 2, with the axle-blank under operation;

and Fig. 6, a transverse vertical section in part, mainly showing a modified construction of the stationary die for making flat or square work.

Referring in the first instance to the first five figures of the drawings, A is the bed-plate of the machine, of sufficient strength to resist any strain that may be thrown upon it, and of any suitable shape or pattern.

B is a housing or main frame bolted on the bed A and of a hollow construction, extending throughout a considerable length of the bed A. In the upper part of this frame B is or may be formed a chamber to receive a loose flanged wheel or former, C, fitted to turn freely upon a stud, b, suitably carried by and secured within the frame.

D is another frame, arranged to fit within the main frame B and to project at its base beyond it. At each end and intermediately of the length of this frame D are formed bearings or supports c c c for the main shaft E of the machine to rotate in. The base of the frame D is made inclining upwardly in a backward direction, as shown at d d, for the purpose of securing to said frame an up-and-down motion within upright corner-guides e e e e on the bed-plate, said motion being produced by means of a sliding wedge-plate, F, arranged to move horizontally in a longitudinal direction on or in ways on the bed-plate A and under the inclined base of the frame D by means of a screw, S, having its bearing in the stationary main frame B, and working in or through a nut or screw-threaded lug, f, attached to the wedge-plate F.

Upon the horizontal main shaft E, that has its bearings, as described, in the uprights e of the rising and falling frame D, is mounted a loose flanged wheel or former, C', in the same vertical plane as the upper wheel, C, of which it is a counterpart. These wheels C C' are driven by the frictional contact of the article under operation or portion thereof in between them, and their object is to produce a varied diameter of the work at such part—as, for instance, in case of the work being a vehicle-axle, to form a collar, g, on the axle-blank G. Where no such or other difference in diameter of the article to be forged is required, 100

then these wheels, that may be of any desired configuration on their peripheries, may be dispensed with.

Fast upon the main shaft E, next to the wheel C, where such is used, is a cylindrical spirally-grooved steel roller, H, which may be of any required length and diameter, and secured on said shaft E, back of the main frame B, is a spur-gear, I. Next to this spur-gear I, on the same shaft E, is an arm or link, J, fitted loosely upon said shaft and projecting laterally therefrom. The outer end of this loose arm J is constructed to fit freely within and is held in position or supported by a slotted or hook-shaped bearing, h, on the upper end of a standard, K, mounted and secured on the bed-plate A.

Secured upon opposite ends of a shaft, i, carried by the outer end of the arm or link J, are a spur-gear, L, and pinion M. The pinion M engages with the spur-gear I, and the gear-wheel L with a pinion, N, fast upon a sleeve, O, which is loose upon the shaft E, and which has attached to it the belt-driven pulley P, by which motion is communicated to the machine. Power being applied to the pulley P causes the pinion N on the loose sleeve O to rotate the shaft i through the wheel L, and by the pinion M the wheel I, main shaft E, and spirally-grooved roller H, fast on the main shaft, are caused to rotate in a given direction. Furthermore, it should be observed that when the frame D, which carries the driving mechanism, is raised or lowered by the turning of the screw S and movement of the longitudinally-sliding wedge-plate F, the arm or link J is retained in position by the slotted or open-sided bearing h of the standard K, and is free to slide or move therein, thus admitting of the frame D being raised and lowered, or, in other words, having a free up and down movement, without disturbing or interfering with the proper engagement of the connected gears.

Within a recess in the main frame B, above or over the spirally-grooved roller H of the rising and falling frame D, is secured, by keys or otherwise, the stationary die Q, which is or may be constructed with a lower back or lip, k, Fig. 3, that, as shown in Fig. 4, may be constructed with a series of teeth, l, for a similarly-toothed spring-follower, R, to work up within, and the toothed portion l^o of which follower forms a continuation of the back k for the work under operation to rest against, and to prevent it from being worked out from between the stationary die Q and the rotating roller-die H by the action of the latter. The back or stop k is arranged at a suitable distance on the off side of the roller H from a vertical line or plane passing longitudinally through the center of the roller, and the spring-follower R is secured at its back end to a standard, m, Fig. 5, of the main frame B. The forward and upper or free end of said spring-follower R rests upon and extends the whole length, or thereabout, of the spirally-grooved

roller H, in line with the back k of the die Q, and said follower by its elasticity will adapt itself to varying heights of the roller, the teeth l^o of the follower and fixed die working up or down between each other and forming a barrier or wall for the work to hold it in place.

Prior to entering the blank—axle-blank G, for instance—to be operated on, the wedge-plate F is drawn back by the screw S to lower the frame D, and so increase the distance between the flat or stationary die Q and the spirally-grooved roller or rotating die H sufficiently to receive the axle-blank G between them. Said blank, being properly heated, is then inserted through an open guide, T, to its place between said dies, in parallel relation, or thereabout, with the axis of the rotating die, as shown in Figs. 2, 3, and 5, and the motion of the screw S reversed to bring the work up to its proper position and to maintain an upward pressure on the blank. The spirally corrugated or grooved roller-die H rotates as indicated by arrow z in Fig. 5, drawing the inner end of the blank G up against the back k of the upper die, Q, and front end of its spring-follower R, the spirally-corrugated surface of the roller H acting obliquely on the fibers of the blank to give them twist as the same are extended or drawn out, much as or in the same manner as rifle-barrels are made, thus adding materially to the toughness of the blank. During this action the upward pressure of the rotating die H is continued, and the portion of the axle-blank under operation between the dies is forged to shape and reduced from the size represented for it by full lines, Fig. 5, to that shown for it by dotted lines, same figure, the spring-follower R closing within the back k of the fixed die to maintain the integrity of the back support or stop for the work as the roller-die is raised, and by working with the roller the follower establishes a downward extension of said stop for the work as it is introduced to the machine. The blank G is of course rotated while being operated on by the dies, motion being given to it by the corrugated roller H, and a sufficient resistance being thrown upon it by the fixed die Q to cause the corrugated surface of the roller to crush into the metal, and thereby produce at the same time both a rotary motion of the blank and drawing action on the metal, which, by the continued upward pressure given by the up movement of the rotating die, will speedily reduce the blank to any required size, and give it a true or proper shape without unduly straining the fibers of the metal, after which the motion of the screw S is reversed to lower the frame D, when the forged blank may be removed and a new heated blank inserted to continue the work.

During the forging of the blank, as described, the loose wheels C' will operate to form the collar g on the blank, or any number of collars may be so formed, and they may be of any desired shape; or, as hereinbefore men-

tioned, for plain work they may be altogether dispensed with.

For round work, tapering in direction of its length, the stationary die Q may be constructed or arranged so that its acting surface inclines in a proper direction relatively to the longitudinal axis of the roller-die H, the axis of which may also be set inclining, if desired, or the outer surface of which may be made 10 tapering.

Pipes, tubes, and other hollow cylindrical or tapering articles may be made with the same facility and in the same manner as solid articles of like exterior configuration, it only 15 being necessary to introduce within the hollow heated blank, when or before inserting it in the machine, a suitable arbor or mandrel.

The working face of the roller-die may, instead of being corrugated throughout its 20 length, be made smooth at its end, as shown at r, for the purpose of giving a smooth finish to the work, by subjecting it to the action of such part after it has been drawn out, or as it is being drawn out from off the corrugated 25 surface of the roller.

The up-and-down motion of the frame D, carrying the rotating die H, may either be effected automatically or by hand or by foot, as desired. Thus it might be done by a foot- 30 lever, from which the operator would raise his foot when required to drop the roller-die sufficiently to introduce the work, and afterward, as said roller rotates toward the operator, applying his foot to the lever with any required 35 amount of pressure to raise the roller-die and keep it forced up against the blank. In the drawings, however, an automatic feed of the roller-die is shown. Thus upon the loose sleeve O is an eccentric, A', the rod a' of which is made 40 to vibrate an adjustable or slotted lever, b', upon a rock-shaft, c', that carries an arm, d'. This arm is connected by a link, e', with a rocking T-lever, f', that has its fulcrum above at g' in a slotted support, h', and has its upper op- 45 posite side arms connected, respectively, with links i' i'', the one of which, i', is pivoted at its outer end to the support h', while the other link, i'', is connected at its outer end with a sliding bar, k'. In this way the lever f', the 50 fulcrum g' of which is free to slide in the slot of the fixed support h', is connected with said support and with the sliding bar k' by a double knuckle joint. This sliding bar carries two pawls, l' m', which engage alternately 55 with reverse ratchet-wheels B' B'', of different diameters, fast on the screw S, the pawl l' en- 60 gaging with the larger ratchet-wheel, B', to give the rising or feeding motion to the roller-die H, and the pawl m' engaging with the smaller ratchet wheel, B'', to give a quicker return or back motion to the screw and corresponding drop to the frame carrying the roller-die.

Upon the sliding bar k' is another sliding 65 bar, n', having one of its ends in gear with a hook on the pawl m', which is further pro- 60 vided with a finger, o'. Upon sliding the bar

n' in the one direction it throws the pawl m' into engagement with the ratchet-wheel B', to quickly work back the screw S and drop 70 the rotating die H, and at the same time, by the finger o', lifts the pawl l' from engagement with the feeding ratchet-wheel B''. An opposite movement of the sliding bar n' just reverses the action of said bar, then pulling on 75 the hook of the pawl m', to release said pawl from the wheel B'', and to allow of the pawl l' dropping into engagement with the wheel B'. This adjustment of the reversing sliding bar n' may be effected by hand, or it may be 80 done automatically by any suitable mechanism connected with the machine, and so that the rotating die H will be raised to the necessary height to complete the work and afterward lowered sufficiently to introduce 85 another heated blank to the machine, giving the operator an opportunity in the interval to attend to his fire and keep several blanks heated at the same time, and so expedite the work done by the machine. 9c

When doing flat or square work instead of rounded, as hereinbefore described, the fixed die Q should be made plain on its face, like that of an anvil—that is, without any projecting back piece or angular extension, as 95 shown in Fig. 5 of the drawings—and the blank G' be entered between said die and the rotating roller H, which will be forced up to the work, as hereinbefore described, and will feed or pass the blank in between it and the fixed 100 die.

In some cases, instead of the rotary die H being moved up and down, the resistance-die Q may be raised or lowered relatively to the rotary die, or both dies may be so adjusted. 105

I am aware that it is not new to roll metal blanks between suitably-shaped rotary and fixed dies, said dies having properly-shaped concavities or projections for imparting the desired shape to the article, and I do not desire to claim any such construction as of my invention; but I am not aware that a forging-machine has ever been constructed in which a spirally corrugated or grooved rotary die was used. 115

The advantage of this particular form of die is, that owing to the constant indentation and flattening of the surface of the bar by the frictional contact of the spirally-corrugated rotary die, a very highly-refined surface is produced, 120 and one at the same time having great strength.

Having thus described my invention, what I claim as new, and desire to secure by Letters Patent, is—

1. In mechanism for forging metal articles, 125 the combination of a rotating die, having spiral corrugations or grooves on its outer or acting surface, with a non-rotating resistance-die and the means, substantially as set forth, for adjusting said roller-die, and both being arranged for operation upon the heated blanks as the same are passed or held between the dies, essentially as described. 130

2. In mechanism for forging solid or hollow

- cylindrical articles, the combination of a plain or flat resistance-die, having a stop at the back end for holding the blank in its place, with a corrugated or obliquely grooved rotary die 5 and the means, substantially as set forth, for adjusting said roller-die, and both being arranged for operation upon the heated blank under arrest by the stop, substantially as specified.
10. 3. In a machine for forging cylindrical articles, solid or hollow, the combination of the stationary resistance-die Q, having a rear stop or back extension, k, and the rotary rising and falling roller-die H, constructed with 15 spiral or oblique corrugations on its acting surface, essentially as and for the purpose herein set forth.
4. In a machine for forging cylindrical metal articles, the combination, with the fixed resistance-die Q, having a back projection or stop, k, of the spring-follower R, constructed to co-operate with said stop, and the rotary rising and falling roller-die H, constructed with spiral corrugations or grooves on its periphery, essentially as described.
25. 5. In a machine for forging cylindrical metal articles, the combination, with the rotating die H, of the frame D, carrying the same, the sliding base wedge plate or device F, for raising and lowering said frame, and the means, substantially as described, for operating the wedge plate or device, substantially as specified.
30. 6. The combination of loose wheels or formers C C' with the rising and falling rotary die H and non-rotating resistance-die Q, essentially as and for the purpose herein set forth.
7. The combination, with the rotary forging-die H and its rising and falling frame D, of the shaft E, the spur-wheel I thereon, the loose sleeve O, pulley P and pinion N, the fixed open-mouthed standard K, shaft *i*, pinion M, wheel L, and the loose link or arm J, connecting the shafts E and *i*, substantially as specified.
45. 8. The combination of the fixed outer main frame, B, the inner rising and falling frame, D, the forging rotary die H, carried by said inner frame, and the means, substantially as described, for raising and lowering the same, 50 essentially as specified.
9. The combination, with the rising and falling rotary die H and the non-rotating resistance-die Q, of the means, substantially as described, for automatically raising and lowering the die H, substantially as specified.
55. 10. The combination, with the rotary forging-die H, its rising and falling frame D, and the main shaft E, of the sliding base wedge-plate F, the screw S, the eccentric A' and rod *a'*, the lever *b'*, the rock-shaft *c'*, the arm *d'*, link *e'*, and lever *f'*, having a sliding fulcrum, *g'*, the slotted support *h'*, the links *i'* *i''*, the sliding bar *k'*, the upper pawl, *l'*, and lower pawl, *m'*, provided with a finger, *o'*, the reversing ratchet-wheels B' B'' on the screw S, and the tripping-slide *n'*, substantially as and for the purposes herein set forth.

MARIE E. SHAY.
